UNITED STATES PATENT OFFICE.

ALEXANDER D. STEWART AND ROY VAGG, OF HAMILTON, ONTARIO, CANADA.

TUCKING MECHANISM FOR KNITTING MACHINES.

Application filed January 16, 1924. Serial No. 686,501.

To all whom it may concern:

Be it known that we, ALEXANDER D. STEWART and ROY VAGG, both of the city of Hamilton, in the county of Wentworth, 5 Province of Ontario, Canada, subjects of the King of Great Britain, have invented certain new and useful Improvements in Tucking Mechanism for Knitting Machines, of which the following is a specification.

10 This invention relates to knitting machines and more particularly to that type adapted to produce open or tuck stitches and our object is to provide means for bringing any desired number of the needles for 15 forming the tuck stitches, into and out of their tucking action when desired and for causing the remainder of said needles to constantly knit.

We attain our object by means of the constructions hereinafter described and illustrated in the accompanying drawings in which

20 Fig. 1 is a front elevation of part of a knitting machine showing my improvements thereon;

Fig. 2 a plan view of the same;

Fig. 3 a development of the knitting cams and part of the needle support surrounding the revoluble needle cylinder;

30 Fig. 4 a detail in side elevation of the sliding cam mechanism for preventing or causing the long latched needles to knit;

Fig. 5 a detail in side elevation of the independent mechanism for controlling and actuating the desired number of the long latched needles to constantly knit;

40 Fig. 6 a diagrammatic view showing the arrangement of the series of long latched needles with their jacks in the series of short latched needles;

Fig. 7 a diagrammatic view showing the relative position of the loops on the short and long latched needles after being moved sufficiently to cast off the loops on the former;

45 Fig. 8 a side elevation of a stocking showing one design formed therein by my improved machine; and

50 Fig. 9 a view similar to Fig. 3 showing diagrammatically the action of the various cams.

55 1 is part of a rotary knitting machine frame on which a table 2 is carried. A needle cylinder 3 is suitably journaled to rotate in the said table and is driven in the

usual manner from driving mechanism (not shown). A series of knitting instruments comprising needles 4 having short latches 4^a are arranged within grooves in the needle cylinder 3 in the usual manner to be reciprocated vertically therein by appropriate knitting cams 5, including the stitch cams 5^a and 5^b and the guide cam 5^c. This series of needles is divided into two substantially equal groups, one of which has 60 short butts 4^b and the other relatively long butts 4^c. The short butt needles are used for knitting the heel and the back portion of a stocking, while the long butt needles are used for knitting the instep and the 70 front portion of the stocking. The purpose of the different lengthed butts is to enable the long butt needles to be thrown out of action during the knitting of the heel, which is well known in the art.

75 To produce open or tuck stitches in the tubular stocking as it is being knitted, a second series of knitting instruments is provided (see Figs. 6 and 7). These instruments are arranged in series in the first 80 series of instruments 4 and each instrument comprises a needle 6 having a long latch 6^a, relative to the latch 4^a, and a jack 7 provided with a butt for a purpose which will 85 hereinafter appear. In the open work clock design shown in Fig. 8 and formed by tuck stitches it will be noted that the latter are positioned substantially midway of the forward and rear centre lines, indicated at F and B respectively, of the stocking. In 90 other words the pattern is formed on each side of an imaginary line separating the work done by the short and long butt needles 4 which necessitates the long latched needles 6 having short and long butts 6^b and 6^c 95 which are respectively arranged in the short and long butt groups of the short latched needles 4. Each long latched needle is positioned between two short latched needles. It will readily be understood that the long 100 butt needles 6 will be thrown out of action with the long butt needles 4 when the heel is being knit as hereinbefore mentioned.

105 It will also be understood that if desired all the long latched needles may be placed in either group of the short latched needles series by providing them with butts similar to the butts of the group in which they are placed. The use of long latched needles 110 inserted in a series of short latched needles

for producing tuck stitches is well known in the art as is also the manner of forming these stitches which consists in preventing the casting-off of a loop formed on the 5 long latched needle for a number of courses, but in feeding the yarn thereto through all said courses so that a collection of a loop and a part or parts of loops will be formed on the needle and when the desired number 10 has been collected all of these are cast off together and over a subsequently formed loop.

The method employed to obtain the above results is briefly described as follows. All 15 the needle butts 4^b, 4^c, 6^b, and 6^c are adapted to engage the knitting cams 5 and be functioned thereby in the usual manner. The upper side of either one of the stitch cams 5^a or 5^b, depending on the direction 20 of rotation of the needle cylinder, is adapted to elevate all the needles relative to a yarn feeding means (not shown) whereby yarn or thread is fed to all the needle hooks on each course. The elevating cam is also 25 adapted to carry the short latches 4^a of the needles 4 upwardly through loops already formed on the needles so that these loops will drop below the latches and thus clear the latter to permit the thread fed to the 30 needle hooks to be drawn through the loops when these needles descend. This is caused by the needle butts engaging the underside of either one of the cams 5^a or 5^b. The loops which were on the needles 4 are thus 35 cleared or cast-off during each course and the thread pulled through them forms a new loop on each needle. Referring particularly to Figs. 3 and 9, it will be noted that the cam 5^a is used for elevating the needles when 40 the needle cylinder is in its normal direction of rotation as indicated by arrows in these figures. The upper end 5^a of the cam 5^a is slightly lower than the upper end of the cam 5^b to ensure that the cam 5^a will 45 only raise the short latched needles 4 to clear their latches and this movement is insufficient to cause the long latches 6^a of the needles 6 to pass through the loops already 50 formed on their needles, see Fig. 7. Therefore the latches of these needles are not 55 cleared and when each of the needles 6 descends the loop thereon is again drawn down by the needle hook together with the yarn or thread fed thereto, thus preventing the casting-off of the said loop.

From this description it is evident that 60 by raising the long latched needles 6 sufficiently during each course they will clear their latches and thus cast-off their loops to constantly knit in the same manner as the needles 4, and by only raising them a sufficient distance periodically their latches are cleared of the first loop and a subsequent part or parts of loops which are cast-off 65 over the last thread supplied to the needle

hook. This forms a tuck stitch similar to that shown in the United States Patent No. 1,433,386 issued Oct. 24th, 1922.

To cause the long latched needles 6 to be raised sufficiently to clear their latches a 70 vertically slidable cam 31, associated with said knitting cams 5, is provided (see Figs. 9, 4, 3 and 2). The cam 31 is slidably mounted in a stationary needle support 5^e which is of usual contour having the inclined surfaces 5^f adapted to elevate the needles 75 after they have been drawn downwardly by either of the stitch cams 5^a or 5^b and to also support the needles at their normal level. The type of knitting cams and 80 needle supports shown in the drawings of this application is shown and described in United States Patent 933,443 issued on Sept. 7, 1909. The cam 31 is provided with a pin 8 which extends laterally through a slot 9 85 formed in the support 5. This pin is adjustably connected in any suitable manner with one end of an actuating rod 10, the other end of which is connected by means of a pin and slot connection with one arm of 90 a lever 11. The rod 10 is slidably mounted in a guide 10^a secured to the table 2. The lever 11 is secured to a spindle 12 journalled on the frame 1 and positioned as hereinafter described. The other arm of the lever 11 95 is connected, by means of a link 13, with one end of a second lever 14, the other end of which is adapted to engage a rotating pattern cam 15 having high and low portions 15^a and 15^b respectively formed on its 100 cam surface. This cam is secured to a pattern shaft 16 which is rotated in any suitable manner.

The cam 31 is thus raised and lowered relative to the cam 5^a and to the needle support 5^e by the pattern cam 15, when the high portion 15^a engages the lever 14 the cam 31 is raised to the position shown in Fig. 3 to engage all the butts 4^b, 4^c, 6^b and 6^c and thus cause the needles 6 to be raised 110 sufficiently to clear their latches and thus permit the loops on the needles to be cast-off, the extra movement given the needles 4 does not affect their knitting in any way. A stationary cam 31^a co-acts with the sliding cam 31 to return the needles to their normal position, see Fig. 3. When the low portion 15^b engages the lever 14 the cam 31 is lowered to be flush with or below the level 115 of the upper end of the needle support 5^e as indicated in dotted lines in Fig. 9 so that the needle butts only rise to the top of the needle support 5^e to prevent the long latched needles casting-off their loops as hereinbefore described.

To cause the needles 6 to clear their latches on alternate courses and thus cast-off two loops on every second course instead of one loop in every course we provide the following means. To a constantly rotating 120

part of the knitting machine a pair of cams 17 are secured, preferably these cams are secured to a gear wheel 18 which is driven from the driving mechanism (not shown) 5 and this gear is driven at one-quarter the speed of the needle cylinder 3. The cams 17 are arranged diametrically opposite one another, see Fig. 4, and arranged concentrically on the gear and each cam extends 10 through an arc of substantially 90°. An arm 19 secured to the spindle 12 is provided at its free end with an anti-friction roller adapted to ride over the cams 17 so that during each revolution of the gear, when the 15 lever 14 is in engagement with the low portion 15^b of the pattern cam, the free end of the arm 19 will be alternately raised and lowered twice and thus actuate the spindle 12 to cause the cam 31 to be raised and lowered on alternate revolutions of the needle cylinder.

To control any desired number of the long latched needles 6 to prevent the casting-off of the loops thereof for a determined number 20 of courses and to cause the remainder of the said long latched needles to function to constantly knit the following means are provided. As hereinbefore mentioned each needle 6 is provided with a jack 7, which lies 25 below the needle within the same groove in the needle cylinder, and these jacks are provided with butts having different lengths. In Fig. 6 it will be noted that the two centrally located jacks have short butts 7^a, the jacks adjacent each of the central jacks are provided with relatively slightly longer butts 7^b and the jacks arranged on opposite sides of the second mentioned jacks are provided with relatively slightly longer butts 30 7^c than the butts of the second mentioned jacks. In other words the two centrally located jacks having short butts 7^a are flanked on each side by two jacks having medium butts 7^b, which are also flanked on 35 each side by three jacks having long butts 7^c. A cam 20 is adapted to be moved radially relative to the needle cylinder 3 and into and out of engagement with all or any desired set of the jack butts to respectively cause 40 the engaged jack butts to be raised and thus raise the long latched needles 6 sufficiently to permit the loops on these needles to drop below the latches thereof and thus clear the latter during each course and independently 45 of the cam 31, or to cause the needles 6 arranged above the disengaged jack butts to be entirely under the action of the cam 31, see Figs 3 and 9. When the jack butts are raised the butts of their needles are 50 elevated to the position indicated at 6^d and are adapted to engage the guide cam 5^e whereby they are conditioned to knit in the same manner as the short latched needles 4.

The cam 20 is formed on or secured to 55 a carrier 21 which is slidably mounted in a

suitable guide formed in the table 2. A tension spring 22 having one end connected with the carrier and the other end with a suitable stationary part tends to withdraw the cam 20 from engagement with the jack butts. The end of the carrier remote from the cam 20 is engaged by a bar 23 which is slidably mounted in a guide 24 and is provided with a lateral projection 25 adapted to engage the latter to limit the movement 60 of the slide bar in one direction. This prevents the cam 20 from being accidentally jammed against the periphery of the needle cylinder. One arm of a bell crank 26, pivoted on a suitable stationary part, is adapted to engage the projection 25 and to the other arm of the bell crank is pivotally connected one end of a link 27. The other end of this link is pivotally connected with one arm of a lever 28 the other arm of which is adapted to engage the periphery of a pattern drum 29. A coil spring 30 disposed on the link 27 and engaging a collar thereon and the table 2 maintains the free end of the lever 28 in engagement with the pattern drum. 65 This drum is secured to the rotating pattern shaft 16 and has a high surface 29^a and a series of low surfaces 29^b, 29^c, 29^d formed on its periphery. It will be noted that there are two surfaces 29^b which are located adjacent each end of the high surface 29^a for a purpose which will hereinafter appear. 70 With the above arrangement when the free end of the lever 28 is resting on the high surface 29^a the cam 20 is closely positioned relative to the needle cylinder to engage all the butts 7^a, 7^b and 7^c and thus cause all the long latched needles to be raised a sufficient distance to clear their latches and thus permit them to constantly knit as hereinbefore 75 described. When the drum 29 has been revolved to permit the lever 28 to drop into engagement with the surface 29^b, the bell crank 26 will be actuated to permit the spring 22 to withdraw the cam 20 from engagement with the butts 7^a and thus permit their needles to come directly under the action of the cam 31 and to cause the jack butts 7^b and 7^c to raise their needle 6 sufficiently to constantly clear their latches. 80 When the lever 28 drops into engagement with the surface 29^c the spring 22 will be permitted to withdraw the cam 20 from engagement with the medium butts 7^b and thus permit their needles to also come directly under the action of the cam 31 and to only cause the jack butts 7^c to function their needles to constantly knit. When the lever 28 drops into engagement with the 85 surface 29^d the spring 22 will be permitted to withdraw the cam 20 from engagement with the long butts 7^c and thus permit all the long latched needles 6 to come directly under the action of the cam 31. As the pattern drum is further rotated the free end 90

95 100 105 110 115 120 125 130

of the lever 28 will be engaged by the second of the surfaces 29^b and thus move the cam into engagement with the medium and long jack butts 7^b and 7^c to cause their needles to function to constantly knit and only permit the needles located above the short jack butts 7^a to come under the action of the cam 31. On certain revolutions of the needle cylinder some of the needles 6 will be raised twice, by means of the cams 31 and 20, during one course of knitting, but this extra movement will not affect the knitting in any way.

The mode of operation is as follows. To knit the top part of the leg of the stocking, diagrammatically shown in Fig. 8, the cam 31 is held, by means of the high portion 15^a of the pattern cam 15, in its raised position to condition all the needles 4 and 6 to constantly knit in the ordinary manner. The lever 28 during the knitting of this top portion is riding on the high surface 29^a of the pattern drum 29 and the pattern shaft is being slowly rotated. When the point 25 is reached in the leg of the stocking where it is desired to start the clock, the cam 29 has been rotated to permit the lever 28 to drop into engagement with the low surface 29^b to withdraw the cam 20 from the short butts 7^a. The cam 15 has also been rotated to permit the lever 14 to drop into engagement with the low portion 15^b to cause the cam 31 to be raised and lowered, by means of the cams 17, on alternative courses. This 30 permits the two long latched needles having the short butt jacks to be actuated to only knit on every other course to produce the double row of tuck stitches *a* while the remainder of the long latched needles are being functioned to constantly knit. When the pattern drum is rotated sufficiently the cam 20 is again actuated to miss the medium butts 7^b to produce a wider series *b* of tuck stitches on the stocking and on further rotation of the said drum the cam 20 is further withdrawn from the needle cylinder to lie out of the paths of all the jack butts to produce the widest series *c* of tuck stitches. The cam 20 is then brought into engagement 35 with the butts 7^b and 7^c to cause the double row of tuck stitches *a* to be continued.

From the above it is obvious that any desired pattern may be formed on the stock-

ing by simply rearranging the high and low surfaces formed on the pattern cam and drum.

It will be understood that when the clock is formed at the side of the stocking as hereinbefore described, there will be two similar sets of knitting instruments used, each set being arranged substantially diametrically opposite one another in the series of needles 4 so that a clock will be formed at each side of each stocking.

What we claim is:—

A knitting machine provided with a series of knitting needles provided with butts and short latches; a plurality of knitting needles provided with butts and relatively long latches; a jack for each long latched needle having a butt, the butts of the jacks being of different lengths, said lengths increasing symmetrically and progressively each way from the center of the group of long latched needles; ordinary knitting cams adapted to engage the butts of all the needles during round and round knitting but having an upward range of action sufficient only to cause the short latched needles to knit; a sliding cam associated with the ordinary knitting cams adapted to be brought into position to engage the butts of all the long latched needles to cause them to knit when desired; means for automatically moving the said second cam to its butt engaging position at predetermined intervals; a third cam movable to engage the jack butts to cause any desired number or all the long latched needles to knit during each course, whether the sliding cam is in or out of engagement with the long latched needle butts; and means for automatically moving said cam at predetermined intervals to progressively engage the different lengths of jack butts to progressively bring the long latched needles into action and to take them out of action in reverse order.

Signed at Hamilton this 2nd day of January 1924.
